FIRE STARTER

Stanley J. Jarvis, 38 Canterbury St., Manchester, Conn.

Filed Mar. 25, 1963, Ser. No. 74,106

Term of patent 14 years

(Cl. D81—10)

FIG. 1 is a front elevational view of a fire starter showing my new design;

FIG. 2 is a top plan view thereof; and

FIG. 3 is a perspective view thereof.

The side opposite that shown in FIG. 1 is substantially a mirror image thereof.

I claim:

The ornamental design for a fire starter, substantially as shown and described.
